CLAIM

[21] Appl. No.: 839,899

The ornamental design for a container for processed photographic film, as shown and described.

[22] Filed: Feb. 25, 1992

DESCRIPTION

[30] Foreign Application Priority Data

FIG. 1 is a top, front and side perspective view of a container for processed photographic film, showing our new design;

Oct. 4, 1991 [JP] Japan 3-30134

FIG. 2 is a front elevational view thereof;

[52] U.S. Cl. D3/35; D3/301; D3/74; D3/99

FIG. 3 is a rear elevational view thereof;

[58] Field of Search D3/30.1, 33, 35, 74, D3/94; D14/121; D16/250; D19/76, 90, 75, 206/387, 389, 408, 455

FIG. 4 is a top plan view thereof;

[56] References Cited

FIG. 5 is a bottom plan view thereof;

U.S. PATENT DOCUMENTS

FIG. 6 is a side elevational view thereof from the left of FIG. 2;
